[57] CLAIM

The ornamental design for a side-loading dish and tray cart, as shown and described.

DESCRIPTION

FIG. 1 is a front elevational view of a side-loading dish and tray cart showing our new design, the rear elevational view being identical thereto;

FIG. 2 is a top plan view thereof;

FIG. 3 is a right side elevational view thereof, the left side elevational view being identical thereto;

FIG. 4 is a bottom plan view thereof;

FIG. 5 is a front elevational view of a side-loading dish and tray cart showing a second embodiment;

FIG. 6 is a top plan view of FIG. 5;

FIG. 7 is a left-side elevational view of FIG. 5, the right-side elevational view being a mirror thereof;

FIG. 8 is a rear elevational view of FIG. 5;

FIG. 9 is a bottom plan view of FIG. 5.

FIG. 10 is a perspective view of the first embodiment shown in FIGS. 1 through 4;

FIG. 11 is a perspective view of the second embodiment shown in FIGS. 5 through 9.

-Fig.1.

-Fig.2.
